UNITED STATES PATENT OFFICE

FRED H. SCHABACKER, OF ROCKFORD, ILLINOIS, ASSIGNOR TO ROCKFORD MITTEN & HOSIERY COMPANY, OF ROCKFORD, ILLINOIS, A CORPORATION OF ILLINOIS

CIRCULAR KNITTING MACHINE

Application filed October 21, 1929. Serial No. 401,070.

This invention relates to improvements in circular knitting machines.

In the knitting of ribbed tops for socks or ribbed legs and tops for stockings it is the practice to knit on a flat bed machine the foot and leg, in the case of socks, and just the foot in the case of stockings, and to transfer the last course of the sock or stocking onto the cylinder needles of a circular knitting machine for the knitting of the ribbed top, in the case of socks, or the ribbed leg and top, in the case of stockings. The rib pattern was, of course, produced by the knitting of the cylinder and dial needles, a certain number of stitches being knocked one way alternating with stitches knocked the other way according to the particular pattern desired, as for example, a 1 and 1, 2 and 1, 3 and 1, 2 and 2, or whatever might be desired. This transferring of the work from the one machine to the other was generally preferred to the knitting of the ribbed part separately and sewing the same to the other part of the sock or stocking; because it obviously produced a more serviceable article, but with the unimproved circular knitting machines, it was impossible to produce the wales of the ribbed portion all continuous with the wales in the rest of the stocking, because there was no way of transferring the loops to the dial needles. For example, where all of the loops were transferred to the cylinder needles the ribbed portion was made too heavy and a pronounced ridge or swell was produced at the union, the dial needles being extra needles and throwing an excess of yarn into the ribbed portion. Thus in the case of a 1 and 1 pattern the ribbed fabric would be made twice as heavy as the fabric of the rest of the sock or stocking, and in the case of a 2 and 1 pattern the ribbed fabric would be 50% heavier than the other, and so on. This was, of course, an outstanding objection since it meant higher cost in proportion to the amount of extra yarn used, less comfort, and more or less unattractive appearance. Another objection with that sort of knitting was that holes were left at the beginnings of the wales knitted by the dial needles, these wales not being continuous with the wales in the

rest of the stocking, and of course these holes spoiled the appearance and gave the impression to the purchaser of defects in the knitting. Another objection was that core yarn could not be used because of its being too hard to ravel and because it made the ridges too heavy, and that meant added cost. 55

It is, therefore, the principal object of my invention to provide a circular knitting machine having needle dummies or so-called transfer points alternating with the needles in the cylinder, one for each dial needle, onto which loops are arranged to be transferred or picked when the last course of the leg or foot of a sock or stocking is being transferred to the cylinder of the circular machine, the dummies being arranged to transfer their loops to the dial needles in the knitting of the first course of the ribbed top or leg so that the wales in the latter will be equal in number to and all continuous with the wales in the rest of the sock or stocking. The resulting article is far superior to those produced by the old methods on the unimproved circular machines inasmuch as the knitting at 70 the union between the two fabrics is just as strong as at any other point. As a matter of fact, it is not evident that the one part has been knit on one machine and the other part on another because the wales in the two parts 75 are knit co-extensive. The ribbed part is furthermore of the same weight as the other part and there is absolutely no ridge whatever at the union between the two parts, so that the sock or stocking is much more comfortable to wear and more attractive in appearance. The fact that less yarn is employed naturally means a saving in cost and it is found that core yarn is suitable for this knitting so that the cost is still further reduced. 80

In the machine made in accordance with my invention, I provide three tracks in the cylinder, the lower one for the butts of the dummies, the middle one for the butts of the cylinder needles during knitting, and the upper one for the butts of both the needles and the dummies when they are raised for the transfer of the work thereto. I provide a switch for shifting the dummies from the 85 90 95 100

lower track to the middle track and another switch for shifting the needles and dummies from the middle track to the upper track, the said switches being arranged to be thrown 5 at the same time when it is desired to elevate the needles and dummies for the transfer of the work thereto, and being thereafter arranged to be operated again at the same time to direct the needles properly on the knitting 10 stroke and direct the dummies back toward the lower track. I provide the knitting cam in the form of an adjustable element, for the purposes of tension adjustment, and provide thereon two different cam surfaces, one 15 of which is reached only by the butts of the needles, and the other of which is reached by the longer butts of the dummies so that the one and the same cam is arranged to direct the needles toward the middle track and the 20 dummies toward the lower track, aside from performing the function of determining the tension on the yarn. The dummies are thus arranged to be retracted in the knitting of the first course immediately after transferring 25 their loops to the dial needles and are arranged to remain retracted thereafter.

Referring to the accompanying drawings illustrating my invention—

Fig. 1 is a plan view of a circular knitting 30 machine embodying my invention;

Fig. 2 is a side view of a portion of the circular frame showing the lever for operating the switch for shifting the needles and dummies from the middle track to the upper 35 track;

Fig. 3 is a central vertical section taken on the line 3—3 of Fig. 1;

Fig. 4 is a fragmentary vertical section 40 showing the knitting cam and is taken on the line 4—4 of Fig. 7;

Fig. 5 is a similar section showing the switch for shifting the dummies from the lower track to the middle track and is taken on the line 5—5 of Fig. 6;

Figs. 6 and 7 are developed views of the 45 inside of the circular frame showing the tracks and illustrating the operation of the dummies with the needles and the control thereof by means of the switches and the knitting cam;

Figs. 8 to 10 are fragmentary views on an 50 enlarged scale showing the transferring of a loop from a dummy to a dial needle;

Fig. 11 is a fragmentary sectional detail on an enlarged scale indicating the knitting of 55 the dial needles with the cylinder needles after the transfer of the loops to the dial needles;

Fig. 12 is a detail on an enlarged scale 60 showing the union between the plain fabric and the ribbed fabric; and

Fig. 13 is a view of a sock produced in accordance with the invention.

The same reference numerals are applied to corresponding parts throughout the views.

Referring for the present, more particu-

larly to Figs. 1 and 3 the stationary circular frame is shown at 14 having a bearing 15 in the base thereof for the driving gear 16 which is attached to the cylinder 17. The latter projects upwardly through the circular frame 70 in the usual manner and has the usual driving lug 18 thereon arranged by engagement with a lug 19 provided on the dial 20 to turn the dial with the cylinder relative to the stationary head 21. An arm 22 mounted on a post 23 on the frame of the machine reaches over the cylinder and carries a standard 24 on which the dial 20 is mounted for rotation as clearly indicated in Fig. 3 and on which the head 21 is fixed. The arm 22 is arranged to be raised and turned to carry the dial to an out of the way position when work is being transferred onto the cylinder needles 25, as is well known, and after the transfer of the work the arm is swung back and fastened 75 rigidly in the position shown and the lug 18 brought into engagement with the lug 19 so as to drive the dial 20 with the cylinder 17 and cause the operation of the dial needles 26 along with the cylinder needles 25 in the usual way. A track 27 is provided for the butts 80 of the needles 26 in the head 21, concentric with the standard 24 and in connection with this circular track a side track 28 is provided into which the needles are switched by the shifting of the lever 29 provided on the head 21 to communicate in and out motion to said needles. This is, of course, a feature common to all circular knitting machines. The head 21 provides support for the yarn carrier 30. The machine as thus far described is 85 purely conventional and no invention is claimed therein except only insofar as the features now to be described cooperate therewith in novel combinations and arrangements 90 required in the practicing of my invention. 100

In the ordinary unimproved circular knitting machine the circular frame 14 is provided with two tracks 31 and 32, the one above the other, but in accordance with my invention I provide a third track 33 below the others, for a purpose which will presently appear. For the sake of convenience 31 will be hereinafter referred to as the upper track, 32 the middle track and 33 the lower 105 track. Now, the cylinder needles 25, which are mounted for reciprocation in slots 34 in the periphery of the cylinder 17, have the butts 35 thereof arranged to travel either in the upper track 31 or the middle track 32 depending on the position of a switch 36, that is, in either the upper or lower track of an ordinary circular machine where only two tracks are provided. The middle track 32 has a rise 37 at one point thereof, adjacent the yarn carrier 30, up which the butts are arranged to ride when the needles are running in the middle track, and if the switch 36 is raised to the position shown in Fig. 6 the butts 35 will ride over the lower 110 115 120 125 130

cam surface 38 of the switch and enter the upper track 31 and thereafter the needles will continue to run in the upper track so long as the switch remains in the position 5 stated. However, when the switch 36 is lowered to the position shown in Fig. 7 the butts 35 riding in the upper track 31, upon coming into engagement with the upper cam surface 39 of the switch 36 are arranged to 10 be directed downwardly away from the upper track along a descending cam surface 40 provided on the so-called knitting cam 41, and thereafter the needles will continue to run in the middle track and be given an up 15 and down knitting stroke each time they traverse the rising and descending cam surfaces 37, 39 and 40. The knitting cam 41 has a rising cam surface 42 extending from the lower end of the descending cam surface 20 40 and arranged to direct the butts of the needles back to the middle track 32 at the end of the knitting stroke. The tension on the yarn is enough to insure the riding of the butts of the needles upwardly along the 25 surface 42. In fact, the knitting cam 41 is adjustable as a whole up or down to determine the extent of the tension on the yarn, a pin 43 being provided extending from the back of the cam 41 outwardly through a slot 30 44 in the frame 14 to any suitable means for fixing the cam in any desired position of adjustment. The switch 36 is operated somewhat similarly by means of a bolt 45. The latter extends through a hole in a lever 35 46 and through a slot 47 in the frame 14 and threads into the back of the switch 36. The lever 46 is pivoted on the frame at 48 and a coiled compression spring 49 under the head of the bolt 45 presses against the lever 46 40 and holds it yieldingly on either one of two pins 50 or 51, holes being provided in the lever 46 on either side of the bolt 45 for reception of said pins in a manner believed to be self-evident. The lever 46 is shown in 45 Fig. 2 in a position corresponding to the lowered position of the switch 36 shown in Fig. 7. Leaving out of consideration for the moment the lower track 33, it will be understood that in the ordinary unimproved circular knitting machine, if there were two cylinder needles for every dial needle, a 2 and 1 rib pattern would be produced by the operation of the cylinder needles and dial needles into each other, and if three cylinder 50 needles were provided for each dial needle a 3 and 1 rib pattern would be produced, and so on. In Figs. 6 and 7 every three cylinder needles 25 are shown alternating with a needle dummy or transfer point 52 from 55 which loops are arranged to be transferred to the dial needles of which there is one for each dummy, so that a 3 and 1 rib pattern would be produced by the operation of the cylinder needles and dial needles into each 60 other following the transfer of the loops 65 from the dummies to the dial needles in the manner hereinafter described.

The dummies 52 have the butts 53 thereof arranged normally to ride in the lower track 33. The dummies are then in lowered retracted position as represented at the right hand end of Fig. 7. A switch 54 is, however, arranged to be thrown down into the path of the butts 53 in the manner indicated in Fig. 6 to direct the dummies to the middle track. 70 The upper ends of the dummies are thereby brought into the same plane with the ends of the cylinder needles running in the middle track. After the dummies have been shifted from the lower track 33 to the middle track 32 they are arranged to be shifted to the upper track 31 along with the cylinder needles 25 by the shifting of the switch 36. The operation of the latter was previously described. The switch 54 is swingable from the inoperative position shown in Fig. 7 to the operative position shown in Fig. 6 about a pin 55 as a center by the turning of a finger piece 56 attached to and extending radially from the outer end of the pin 55, as shown in Fig. 5. 75 A leaf spring 57 fastened to the circular frame 14, as shown at 58, is arranged to hold the finger piece 56 yieldingly in either of its two positions. Assuming that the switch 36 has been shifted to the raised position shown in Fig. 6 simultaneously with the shifting of the switch 54 or immediately thereafter, it should be evident that after one complete turn of the cylinder all of the needles 25 and dummies 52 will be disposed in the upper track 31 and 80 hence will be projecting from the cylinder as far as possible as shown in the middle of Fig. 6, the ends of the needles and dummies being all disposed in the same plane. When the needles and dummies are so disposed the loops of the last course of knitting of a piece of work are arranged to be transferred or picked thereon, one loop onto each needle and one loop onto each dummy. Now, it will be observed that the upper ends of the dummies 52 85 resemble closed tweezers, there being a pair of spaced spring tines 59 forming the upper end of each dummy having the extremities 60 thereof bent inwardly toward and engaging one another in such a way that the end of the dummy is blunt and rounded so that a loop can be slipped over the same just as easily as over the end of any one of the cylinder needles. The tines of each dummy are spaced sufficiently to form an eye arranged to receive 90 the end of the dial needle 26 associated with the dummy. The tines are arranged to be sprung apart to allow the dial needle to emerge from the eye as the dummy is drawn downwardly therefrom as depicted in Fig. 7. 95 Spurs 61 are provided on the edges of the tines 59 at the proper distance from the free ends of the tines, as most clearly shown in Figs. 8 to 10, so that the loop when transferred to the dummy will come into the 100 105 110 115 120 125 129

proper plane with reference to the dial needle associated with the dummy. The purpose of this precise location of the loop by means of the dummy will be hereinafter explained. The working into each other of the dial needles and cylinder needles, with the dial needles entering the eyes of the dummies as represented in the middle of Fig. 7, results in the knitting of the first course of the rib pattern and the transferring of the stitches from the dummies to the dial needles, and, consequently, after one complete turn of the cylinder the dummies should all be retracted as they take no further part in the operation of the machine. For that reason, immediately after transfer of the stitches to the dial needles the dummies are arranged to be directed back to the lower track 33. The butts 53 of the dummies 52 ride down the descending cam surface 40 of the knitting cam 41 along with the butts 35 of the cylinder needles as represented in Fig. 7, but by reason of the fact that the butts 53 are longer than the butts 35 the butts 53 are arranged to ride on a descending cam surface 62 instead of riding up the ascending cam surface 42 with the butts 35 of the cylinder needles 25. This operation is clearly shown in Figs. 4 and 7, the latter showing how the dummies are separated from the cylinder needles, the dummies going to the lower track 33 and the cylinder needles to the middle track 32. The switch 54 is, of course, shifted to the inoperative position shown in Fig. 7 at the same time the switch 36 is shifted to the lower position so that after the first turn of the cylinder the dummies always remain retracted whereas the cylinder needles are each given a knitting stroke once for each turn of the cylinder.

In describing the operation, assume that it is desired to produce a sock such as that shown in Fig. 13 having a plain foot 63 with any suitable or preferred toe and heel portions 64 and 65 and a plain leg portion 66, but having a ribbed top 67, say of a 3 and 1 pattern. Everything but the ribbed top can, of course, be produced on an ordinary flat bed knitting machine. The rib top however, requires transferring of the work to a circular knitting machine. In Fig. 12 the letter A designates a portion of the last course of knitting for the leg 66 shown in white, and B represents the first course of the knitting for the ribbed top 67 shown in solid black. In the transferring of the work to the circular machine all of the loops of course A are slipped over or picked onto the cylinder needles 25 and dummies 52, the needles having the latches thereof open and the loops being slipped down over the same past the latches to the throats of the needles so that these loops will be shed in the knitting of the first course of the ribbed top. The loops intended to be transferred to the dial needles, and for that reason, picked onto the dummies 52, are brought down onto the spurs 61. To aid in the transferring of the work it is customary to knit a few extra courses on the leg with yarn of a contrasting color and this yarn is simply unraveled after the last course of the leg proper has had all of the loops thereof properly transferred onto the cylinder of the machine as just described. After the dial has been brought into position and the driving lugs 18 and 19 are in engagement the switch 29 is thrown so that the dial needles will be given the in and out motion required for knitting therewith, and then the cylinder is given one turn or more by hand to give the dial needles and cylinder needles an opportunity of working into each other with the dial needles entering the eyes of the dummies to transfer the loops from the dummies to the dial needles. Then the clutch for turning the cylinder and dial under power is engaged and the ribbed top is produced of a predetermined length, the clutch being disengaged automatically at the proper instant to stop the operation of the machine for the removal of the finished sock. In the first turn of the dial, which as stated above is taken care of by hand, the dial needles are extended through the eyes of the dummies and the loops of the end course A thereon as represented in Figs. 8 and 9, the dial needles being extended far enough so that the loops are transferred onto the throats of the dial needles behind the latches thereof. As the dummies commence to descend toward retracted position and the dial needles commence to be retracted on their knitting stroke it is evident in Figs. 10 and 11 that the loops of the end course A are shed from the dial needles over the yarn cast into the hooks of the dial needles, the latches of said needles closing in the shedding of said loops. By reference to Fig. 12 it will be seen that the stitches of the dial needles designated by the letter C are knocked one way whereas the stitches of the cylinder needles designated by the letter D are knocked the other way to produce the rib pattern in a well known manner.

It is believed the foregoing description is sufficient to give a clear understanding of my invention such that anyone skilled in the art would be enabled to practice the same. The appended claims have been drawn with a view to affording protection commensurate with the degree of novelty and in order to cover all legitimate modifications and adaptations such as would be apt to occur to one skilled in the art having the benefit of my disclosure.

I claim:

1. In a circular knitting machine, the combination of a circular frame, a cylinder rotatable therein, a dial cooperating with the cylinder and rotatable therewith, the cylinder having needles operable thereon and the

dial having needles operable thereon in transverse relation to one another, said frame having a pair of continuous tracks thereon one above the other in either of which the cylinder needles are arranged to be disposed, at one level for the transfer of work thereon and at the other level for knitting, means for switching the needles from one track to the other, said frame having a third track at still another elevation, a plurality of transfer points in the nature of needle dummies arranged to be disposed normally on said track at an out-of-the-way level with respect to the cylinder needles but adapted to be switched to one of the other tracks to the same level as the cylinder needles when the latter are having work transferred thereto whereby to have certain stitches transferred onto said transfer points, the latter being arranged subsequently to transfer the stitches therefrom to the dial needles, and means for switching the transfer points to and from the last mentioned track.

2. A structure as set forth in claim 1 including a knitting cam on said frame arranged to have the butts of the cylinder needles engage said cam surfaces thereon in the normal knitting operation in which the said needles are directed always toward one of the first two mentioned tracks, said cam having still another cam surface arranged to be engaged only by butts provided on the transfer points arranged to direct said points toward the last mentioned track, whereby to separate the transfer points from the cylinder needles during the knitting of the first course of the rib knitting after the transfer of the stitches from said points to the dial needles.

3. A structure as set forth in claim 1 including a knitting cam, the cylinder needles having butts arranged to ride on certain cam surfaces provided on said cam whereby the same are always directed to one of the first two mentioned tracks after the knitting stroke thereof, the said cam having still another cam surface thereon so located that the same is not reached by the butts of the cylinder needles, and the transfer points having longer butts than the cylinder needles provided thereon arranged to ride on the last mentioned cam surface and to be thereby directed toward the last mentioned track whereby to separate the transfer points from the cylinder needles during the knitting of the first course of the rib knitting after the transfer of the stitches from said points to the dial needles.

4. The structure as set forth in claim 1 wherein each of the transfer points comprises a stem portion terminating in a tweezers portion over which the stitch to be transferred is arranged to be slipped and into which the dial needle is arranged to be entered for the transfer of the stitch thereto,

the said tweezers portion having one or more projections thereon at a predetermined distance from the extremity thereof for definitely locating the stitch with reference to the plane of operation of the dial needle for the purpose described.

In witness of the foregoing I affix my signature.

FRED H. SCHABACKER.
